(57) **CLAIM**

The ornamental design for a ceiling fan with light, as shown and described.

DESCRIPTION

FIG. 1 is a front, top perspective view of a ceiling fan with light, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of detail "9" identified in FIG. 2. The dashed broken lines in the figures illustrate portions of the ceiling fan with light that form no part of the claimed design. The dash-dot-dash broken lines in FIGS. 2 and 9 depict the bounds of the enlarged views and form no part of the claimed design.
